CLAIM

The ornamental design for an eye speculum, as shown and described.

DESCRIPTION

FIG. 1 is a perspective view of an eye speculum in accordance with the present design;
FIG. 2 is a top plan view of the eye speculum of FIG. 1;
FIG. 3 is a right side elevational view of the eye speculum of FIG. 1;
FIG. 4 is a left side elevational view of the eye speculum of FIG. 1; and,
FIG. 5 is a front elevational view of the eye speculum of FIG. 1, the rear elevational view being a mirror image of the front elevational view.
